ATTORNEY.

UNITED STATES PATENT OFFICE.

FREDERICK NEUDORFF, OF ST. JOSEPH, MISSOURI.

COVER FOR SPECTACLE-TEMPLES.

989,397.

Specification of Letters Patent. Patented Apr. 11, 1911.

Application filed April 2, 1910. Serial No. 553,093.

To all whom it may concern:

Be it known that I, FREDERICK NEUDORFF, a citizen of the United States, residing at St. Joseph, in the county of Buchanan and 5 State of Missouri, have invented certain new and useful Improvements in Covers for Spectacle-Temples, of which the following is a specification, reference being had therein to the accompanying drawing.

10 My invention relates to improvements in elastic covers for spectacle temples, the objects of which are, to provide an elastic cover of this character which shall be extremely resilient and which, by reason of pressure 15 of same on the skin of the wearer, will not cause stoppage of circulation of the blood and consequent dark lines in said skin, and which will not bruise, abrade or otherwise injure said skin, be it ever so tender, and by 20 the use of which, all annoyance and discomfort to the wearer of same is obviated.

Further objects are; to so construct said cover that the same shall be thoroughly sanitary, be non-absorbent and can readily 25 be washed or otherwise cleaned, and to provide ready means, by which said cover can be easily and quickly placed and secured on, or removed from any of the ordinary spectacle temples now generally in use; also to 30 provide a cover of this character which shall be neat in appearance, substantial, durable, and extremely cheap in cost of manufacture.

I attain these objects by the device illustrated in the accompanying drawing, in 35 which:—

Figure 1 is a perspective view of a pair of spectacles, provided with straight temples inserted in the elastic covers. Fig. 2 is a magnified transverse section, on the line 40 XX, seen in Fig. 1. Fig. 3 is a side elevation of one of the other various forms of temples on which the elastic cover is used, showing said cover on a riding temple. Fig. 4 is a magnified longitudinal section, cut vertically 45 through the center of a portion of a temple and a portion of the elastic cover.

Referring to Fig. 3, the inwardly projecting flutes 3 are formed integral with tube 2 and extend continuously in spiral arrange-

ment throughout the entire length thereof. 50 In this spiral arrangement of said flutes lies the novelty and utility of my invention.

In the manufacture of the elastic cover, the tube 2 and its internal spirally arranged flutes 3 are formed of one piece of rubber, 55 vulcanized in an ordinary tubular metal mold, around a screw threaded metal core, from which the thus formed elastic cover is readily removed by turning and thereby unscrewing the same from said core. Since 60 said mold and core form no part of this invention, the same are neither shown nor described in detail.

In practice the described elastic cover is made of considerable length and is cut into 65 such shorter lengths as are desired for covering practically all of temples 1. In application, temple 1 is inserted in the described elastic cover which is forced thereon with a rotary motion. 70

It will be understood that the flutes 3 render tube 2 very elastic, and by reason of the elastic pressure of said flutes, the same adjust themselves (within reasonable limits,) to snugly fit temples 1 of various shapes and proportions, and by reason of their elastic pressure against said temples, are caused to adhere to the same and are thereby efficiently held in place thereon. 75

Having fully described my invention, what 80 I claim as new and desire to secure by Letters Patent is:—

An elastic cover, formed of a length of elastic rubber tube, having a smooth, non-porous outer surface and provided with a 85 plurality of inwardly projecting, spirally arranged flutes, extending continuously throughout the entire length of said tube and formed integral therewith, in combination with a spectacle temple, snugly inserted 90 in said cover.

In testimony whereof I affix my signature in the presence of two witnesses.

FREDERICK NEUDORFF.
